UNITED STATES PATENT OFFICE.

LEWIS E. BIERY, OF NEW KENSINGTON, PENNSYLVANIA.

BAG-HOLDER.

SPECIFICATION forming part of Letters Patent No. 611,347, dated September 27, 1898.

Application filed October 27, 1897. Serial No. 656,515. (No model.)

To all whom it may concern:

Be it known that I, LEWIS E. BIERY, a citizen of the United States, residing at New Kensington, in the county of Westmoreland 5 and State of Pennsylvania, have invented certain new and useful Improvements in Bag-Holders; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to certain new and useful improvements in bag-holders.

The invention has for its object the provision of a simple and practical device for holding bags in position while filling them with 20 grain, &c., and is especially designed for farm and mill use.

With the above object in view the invention finally consists in the novel construction, combination, and arrangement of parts, 25 as will be hereinafter more specifically described in detail.

In describing the invention in detail reference is had to the accompanying drawings, forming a part of this specification, and wherein 30 in like numerals designate like parts throughout the several views, in which—

Figure 1 is a vertical front view of my improved bag-holder. Fig. 2 is a vertical side view of the same. Fig. 3 is a top plan view 35 of the same on the line A and B of Figs. 1 and 2.

To put my invention into practice, I provide a frame constructed of the two upright beams 1 and 2, which are connected together 40 by the cross-braces 3 and 4 and the base-piece 5. Attached to the lower ends of the aforesaid upright beams by the hinges 6 and 7 is the footboard 8, which may be folded up against the beams when not in use or when 45 it is desired to move the device and set it up in another location. A flat metal hanger-bar 9 of suitable length is obtained, and upon its upper end is formed the hook 9, by which it is suspended to the frame, and about midway 50 down its length and upon its face portion is attached a suitable hook 10. Loosely mounted upon the aforesaid bar is the bracket 11,

which is divided at its forward portion and has the lugs 12 and 12' formed thereon, which are connected together by means of the thumb-screw 13. Loosely fitted within the bracket is the sheet-metal hopper 14, having the upper flared end 14', and upon the lower outside portion of this hopper are attached the flat springs 15, which have the cams 15', pivoted upon their lower ends, for securing the bag or sack to the hopper. A chair 16 is attached to the bracket by means of the eye-piece or lugs 17 and 18, which are formed or attached to the bracket, and the upper end 65 of the chain is attached to the hook 10 of the hanger-bar, so as to suspend the hopper at the required height. Any suitable arrangement may be used for securing the base of the frame and the footboard together when in use. 70

In using the device the bag or sack is fitted upon the lower end of the hopper. The cams are then turned upward, so as to clamp the bag to the hopper. The hopper is then raised or lowered to the required distance and the 75 required amount of grain dumped into the hopper to fill the sack. The cam-clamps are then released and the sack or bag removed.

If it is desired, the frame may be dispensed with and the device suspended by means of 80 the hanger-bar to any convenient support.

Having thus fully shown and described my invention, what I claim as new, and desire to secure by Letters Patent, is—

In a bag-holder, the combination with the 85 uprights, connected together at the top and bottom, by cross-bars, and the hanger formed with a hook at the upper end engaging with the upper cross-bar and provided intermediate its ends with a hook, of the bracket slidably mounted on said hanger, the lugs at the outer end thereof and the thumb-screw passing therethrough, the hopper having a flaring mouth supported by said bracket, the flat springs secured to the lower end of said hopper and the cams pivoted to the free ends of 90 said springs, substantially as shown and described.

In testimony whereof I affix my signature in presence of two witnesses.

LEWIS E. BIERY.

Witnesses:

U. S. COPE,
JOHN GROETZINGER.
